UNITED STATES PATENT OFFICE

2,577,216

DOOR LOCK

Mathew Spinello, Rockford, Ill.

Original application July 9, 1945, Serial No. 603,823. Divided and this application August 17, 1946, Serial No. 691,414

10 Claims. (Cl. 292—173)

1

This application is a division of my application Serial No. 603,823, filed July 9, 1945, now abandoned.

This invention relates to door locks, and is more particularly concerned with improvements in the bore type of locks disclosed in my Patent 2,343,249, issued March 7, 1944, these locks deriving the name "bore type" from the fact that transverse holes in the door made to receive such a lock can be bored with an auger bit, so that there is very little mortising necessary.

The principal object of my invention is to provide in connection with the lock inner and outer door knobs and an operating connection between the inner knob and the bolt, together with a clutch device controllable from the inside of the door by a push and pull button to connect or disconnect the outside knob with the inside knob, while still permitting opening of the door from the outside with a key in the conventional way.

The invention is illustrated in the accompanying drawing, in which

Fig. 1 is a vertical section through a portion of a door showing a bore type lock made in accordance with my invention in which the bolt is retractable at any time by an inside knob and is retractable also by the outside knob subject to inside push and pull button control, and

Figs. 2, 3, and 4 are three views of the clutch mechanism shown in Fig. 1.

The same reference numerals are applied to corresponding parts throughout these views.

Referring to the drawing, the reference numeral 11a designates a door in which transverse holes 12 and 13' are bored with auger bits to receive the lock 14'. 15a is the bolt reciprocable in the housing 16 that is received in the hole 12 and fastened in place in the usual way by an escutcheon plate in a recess mortised in the edge of the door, the bolt having the usual beveled face on the outer end thereof, which faces one way for left hand operation and in the opposite direction for right hand operation. A long coiled compression spring (not shown) urges the bolt 15a normally outwardly. In other words, the bolt is a spring latch which permits slamming the door with the bolt projecting, but, as will soon appear, it requires the operation of the inside knob 62 or the key 23 on the outside of the door to retract the bolt so that the door can be opened, and when the outside knob 61 is interconnected with the inside knob 62, the bolt 15a may be retracted by turning the knob 61 without the necessity of using the key 23.

Outer and inner escutcheon plates are indicated

at 59 and 60, and the clutch device for connecting or disconnecting the outside knob 61 from the bolt 15a is indicated at 63, this clutch device being controllable from the inside of the door by a push and pull button 64. The lock 14' is shown as entered in the hole 13' and clamped in a recess 65 in the outside escutcheon plate 59 from the inside of the door by an attaching plate 66 and screws 27' entered through the attaching plate and threaded in ears 28 provided on the body 29 of the lock. The cylinder 30 of the lock has a loose lost motion connection with the stub shaft 32', as indicated at 31', the free end of the shaft 32' being suitably supported for rotation in a hole 61 provided therefor in the attaching plate 66. The arm 35 for operating the bolt 15a has a rectangular hole 36 provided in the upper end thereof slidably receiving the rectangular shaft 32' for an operating connection. The pin 40 connecting the lower end of the arm 35 to the bolt 15a is tubular and a pin 68 is entered therein to provide another operating connection between the bolt 15a and another arm 69 that is arranged to be turned by means of a square shaft 70 on which the knob 62 is mounted. There is sufficient play in the connection between the arm 35 and the pin 40 to give freedom of movement of the arm 69. The shaft 70 has a swivel connection, as indicated at 71, with another square shaft 72 on which the knob 61 is mounted. The shafts 70 and 72 are adapted to be positively connected to turn together, so that the bolt 15a may be retracted by turning the outside knob 61. The clutch 63 performs this function and is in the form of a sleeve 73 having a square bore 74 which in one position of the sleeve, indicated in dotted lines in Fig. 1, accommodates only the inner end portion of the shaft 70, but in the other position of the sleeve, shown in full lines in Fig. 1, is in overlapping relation to the inner end portions of both shafts. A spring pressed ball detent 75 housed in a hole in the shaft 70 is adapted to enter either of two conical depressions 76 in the bore 74 of the sleeve to lock the sleeve releasably in either of the two positions mentioned. A yoke 77 carried on the inner end of the shank 78 of the push and pull button 64 is entered in an annular groove 79 in the adjacent end of the sleeve 73 to provide an operating connection between the sleeve and the button, so that the sleeve may be moved from one position to the other by push and pull movement of the button 64. Now, it is obvious that unless the shaft 72 is in register angularly with the shaft 70, it would not be possible to move the sleeve 73 in the manner stated,

and for that reason I have provided a spring type registering or detent device 80 made of spring wire and having rectangular loops 81 and 82 on its opposite ends, the loop 81 fitting tightly on parallel flats 83 milled in opposite sides of the sleeve 73, and the loop 82 closely embracing the opposed flat sides of the shaft 72. In that way, it is clear that one may turn the shaft 72 relative to the registering device 80 when the shaft 72 is in decluched relation to the shaft 70, but such turning will be against the spring resistance or detent action of the loop 82, and the shaft 72 will always stop in a position in angular registration with the shaft 70, so that the sleeve 73 can be slipped over the inner end portion of the shaft 72 to connect the shafts 70 and 72 whenever that is desired.

In operation, assuming that the clutch device 63 is in the position shown in Fig. 1 connecting the shafts 70 and 72, one may open the door from the outside by turning the knob 61, the turning of the shaft 70 with the shaft 72 causing oscillatory movement of the arm 69 to retract the bolt 15a. However, when the button 64 is pulled out to the dotted line position shown in Fig. 1, the outside knob 61 is thereby disconnected from operative relation to the bolt 15a and under such conditions the door may be opened from the outside only with the proper key 23.

It is believed the foregoing description conveys a good understanding of the objects and advantages of my invention. The appended claims have been drawn to cover all legitimate modifications and adaptations.

I claim:

1. In a door latch mechanism, the combination with a bolt mounted in a door for reciprocation, an inside manually operable knob having a shaft rotatable thereby, means operatively connecting said shaft with said bolt, an outside manually operable knob having a shaft rotatable thereby coaxially aligned with the first shaft, a clutch device movable on the inside shaft to a position overlapping the end of the outside shaft for detachably connecting said shafts, an inside-operable push and pull button adjacent the inside operable knob and guided for reciprocation in spaced parallel relation to said shafts and operatively connected with said clutch device to move the same positively in either direction lengthwise relative to the inside shaft to connect or disconnect said shafts, and spring pressed means carried on the clutch device and held thereby in a fixed relation to the inside shaft and operatively engaging said outside shaft for yieldably restraining turning of the outside shaft relative to the inside shaft when in decluched relationship thereto and tending to stop said outside shaft always in registering clutchable relationship to said inside shaft and the clutch device.

2. In a door latch mechanism the combination of an inside and an outside knob, square shafts operable thereby and coaxially aligned and swivelly connected, door latch actuating means operable from one of said shafts, a clutch collar having a square bore slidably received on one of said shafts, spring detent means for holding said collar releasably in a retracted position on said one shaft or in a moved position receiving the end portion of the other shaft also, spring detent means for releasably holding said other shaft in registering clutchable relationship to the first shaft, and manually operable means operable from one side of the door for shifting said clutch collar.

3. A clutch of the character described comprising, in combination, two square shafts coaxially aligned and swivelly connected, a clutch collar having a square bore slidably received on one of said shafts, spring detent means for holding said collar releasably in a retracted position on said one shaft or in a moved position receiving the end portion of the other shaft also, spring detent means for releasably holding said other shaft in registering clutchable relationship to the first shaft, and means for shifting said collar.

4. A clutch of the character described comprising, in combination, two like shafts of regular polygonal cross-section coaxially aligned and swivelly connected, a clutch collar having a polygonal bore slidably and nonrotatably received on one of said shafts, spring detent means for holding said collar releasably in a retracted position on said one shaft or in a moved position receiving the end portion of the other shaft also, and a spring wire loop fixed in relation to the collar and slidable on the other shaft in such a way that said other shaft is spring restrained against turning from clutchable registration.

5. A clutch as set forth in claim 3 wherein the spring detent means for releasably holding the other shaft in registering clutchable relation to the first shaft comprises a spring wire loop fixed in relation to the collar and slidable on the other shaft to be clutched thereby in such a way that said other shaft is spring restrained against turning from clutchable registration.

6. A clutch of the character described comprising, in combination, two square shafts coaxially aligned and swivelly connected, a clutch collar having a square bore slidably receiving the end portion of one shaft and adapted to receive the adjacent end portion of the other shaft, the collar having parallel grooves on the opposite sides in a plane normal to the axis of the collar and shafts, and a spring wire registration member for releasably and resiliently holding said other shaft in registering clutchable relationship to the first shaft, said detent member comprising two spaced rectangular loops, one of which fits in the grooves to hold the registration member against turning relative to the collar, and the other of which fits slidably on the other shaft to hold it in register with the bore in the collar.

7. A clutch as set forth in claim 6 wherein the wire registration member is formed to provide two U-shaped loops in spaced parallel relation and interconnected by parallel portions, each connected at one end to the end of one arm of one loop and at the other end to the corresponding end of one arm of the other loop.

8. In a door latch mechanism the combination of an inside and an outside knob, square shafts operable thereby and coaxially aligned and swivelly connected, door latch actuating means operable from one of said shafts, a clutch collar having a square bore slidably received on one of said shafts, spring detent means for holding said collar releasably in a retracted position on said one shaft or in a moved position receiving the end portion of the other shaft also, a spring wire registration member for releasably and resiliently holding said other shaft in registering clutchable relationship to the said one shaft and formed to provide spaced U-shaped jaw portions spacedly interconnected by the ends of their arms, one jaw portion holding the collar and the other holding the other shaft to resist turning relative to the collar, and manually operable means operable from one side of the door for shifting said clutch collar.

9. In a door latch mechanism, the combination of an inside and an outside knob, two like shafts of regular polygonal cross-section operable thereby and coaxially aligned and swivelly connected, door latch actuating means operable from one of said shafts, a clutch collar having a polygonal bore slidably and non-rotatably received on one of said shafts, spring detent means for holding said collar releasably in a retracted position on said shaft or in a moved position receiving the 10 end portion of the other shaft also, spring detent means for releasably holding said other shaft in registering clutchable relationship to the first shaft, and manually operable means operable from one side of the door for shifting said clutch collar.

10. A clutch of the character described comprising, in combination, two like shafts of regular polygonal cross-section coaxially aligned and swivelly connected, a clutch collar having a polygonal bore slidably and non-rotatably received

on one of said shafts, spring detent means for holding said collar releasably in a retracted position on said shaft or in a moved position receiving the end portion of the other shaft also, spring detent means for releasably holding said other shaft in registering clutchable relationship to the first shaft, and means for shifting said collar.
